(57) **CLAIM**

The ornamental design for a hardhat with a protected overhead cooling fan, as shown and described.

DESCRIPTION

FIG. 1 is a top perspective view of a hardhat with a protected overhead cooling fan showing my new design;

FIG. 2 is a front elevation view of FIG. 1 showing a portion of the power cable for the fan;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The evenly dashed lines in FIG. 7 depicting an overhead fan, a portion of the fan charging cord within the interior of the hardhat, and an interior shock absorbing suspension system represent portions of the hardhat with a protected overhead cooling fan that form no part of the claimed design. The dot-dash line represents the boundary of the claim and forms no part thereof.
